CLAIM

The ornamental design for a confectionery product, as shown and described.

DESCRIPTION

FIG. 1 illustrates a front perspective view of the confectionery product;

FIG. 2 illustrates a front view of the confectionery product of FIG. 1;

FIG. 3 illustrates a rear view of the confectionery product of FIG. 1;

FIG. 4 illustrates a right side view of the confectionery product of FIG. 1;

FIG. 5 illustrates a left side view of the confectionery product of FIG. 1;

FIG. 6 illustrates a top view of the confectionery product of FIG. 1;

FIG. 7 illustrates a bottom view of the confectionery product of FIG. 1;

FIG. 8 illustrates a front perspective view of a second alternative embodiment of the confectionery product;

FIG. 9 illustrates a front perspective view of a third alternative embodiment of the confectionery product;

FIG. 10 illustrates a front perspective view of a fourth alternative embodiment of the confectionery product;

FIG. 11 illustrates a front perspective view of a fifth alternative embodiment of the confectionery product; and,

FIG. 12 illustrates a front perspective view of a sixth alternative embodiment of the confectionery product.
